UNITED STATES PATENT OFFICE.

AMBROSE L. DAVIS AND LEVI A. DAVIS, OF PORT CRANE, NEW YORK.

IMPROVEMENT IN VEHICLE-SPRINGS.

Specification forming part of Letters Patent No. 151,009, dated May 19, 1874; application filed March 21, 1874.

To all whom it may concern:

Be it known that we, AMBROSE L. DAVIS and LEVI A. DAVIS, of Port Crane, in the county of Broome and State of New York, have invented a new and useful Improvement in Wagon-Springs, of which the following is a specification:

This invention relates to the construction of the running-gears of wagons and other wheeled vehicles; and consists of springs beneath the fifth-wheel and king-bolt, and in the construction of the clip-block on the axle for fastening and supporting the ordinary springs, the construction and arrangement being as hereinafter described.

In the accompanying drawing, Figure 1 is a plan view, showing the top of the forward running-gear of a spring-wagon. Fig. 2 is a side elevation, showing a forward wheel.

Similar letters of reference indicate corresponding parts.

A is the forward axle. B B represent the ordinary spring confined to the axle, and connected with the tee C of the pole D, and with the rear spring E. E' is a bolster on the rear spring E. F F are springs attached to the tee C of the pole, and to the bolster E. These springs F F we consider a novelty in spring-wagons, and they form the essential feature of our invention. These springs receive the blocks and bars G H, to which the fifth-wheel I is attached, upon which the wagon-body rests, being confined by the king-bolt, through the

hole J. The springs F F act in connection with the other springs of the running-gear, and add materially to the elasticity of the wagon-body. K is the clip-block, by means of which the springs B B are confined to the axle. L is a clip, which passes around the axle and through the block K, and through the spring. This arrangement, we are aware, is not new; but the ends of the block extend from this clip in each direction, and each receives a clip, M, for giving additional support to the spring. This block, therefore, performs a new and important function in the construction of spring-wagons.

Having thus described our invention, we claim as new and desire to secure by Letters Patent—

1. The combination of the springs F with the axle A, tongue-bar C, and rear spring E, all connected as and for the purpose shown and described.

2. The combination of blocks K and clips M with axle A and springs, as shown and described.

AMBROSE L. DAVIS.
LEVI A. DAVIS.
